(57) **CLAIM**

The ornamental design for a brake disc, as shown and described.

DESCRIPTION

FIG. 1 is a front view of a brake disc showing our new design;

FIG. 2 is a left side view thereof;

FIG. 3 is a right side view thereof;

FIG. 4 is a top view thereof;

FIG. 5 is a bottom view thereof;

FIG. 6 is a back view thereof; and,

FIG. 7 is another front view thereof showing the underlying vanes in broken lines.

The broken line portions are for illustrative purposes only and form no part of the claimed design.

1 Claim, 5 Drawing Sheets
